UNITED STATES PATENT OFFICE.

FRED F. INGRAM, OF SAN FRANCISCO, CALIFORNIA, ASSIGNOR OF ONE-HALF TO ALBERT S. WILSON, OF SAN DIEGO, CALIFORNIA.

SPEED-INDICATOR.

No. 874,594.

Specification of Letters Patent.

Patented Dec. 24, 1907.

Application filed May 28, 1907. Serial No. 376,112.

To all whom it may concern:

Be it known that I, FRED F. INGRAM, a citizen of the United States, residing at San Francisco, in the county of San Francisco and State of California, have invented certain new and useful Improvements in Speed-Indicators, of which the following is a specification, reference being had therein to the accompanying drawing.

10 My invention relates to improvements in speed indicators and more particularly to one especially adapted for use upon a marine engine for indicating the number of revolutions per minute of its shaft.

15 One object of the invention is to provide an indicator of this character which will not be affected by the rolling and pitching of the ship and which will be of simple, strong, durable and comparatively inexpensive construction.

20 With the above and other objects in view, the invention consists in the novel features of construction and combination and arrangement of parts hereinafter described and 25 claimed, and illustrated in the accompanying drawings, in which.

Figure 1 is a front elevation of a speed indicator constructed in accordance with my invention; Fig. 2 is a vertical section through 30 the same; and Fig. 3 is a rear elevation of the dial with its casing removed; Fig. 4 is a detail horizontal section through the casing and Fig. 5 is a detailed vertical section through the sleeve 23 and the upright 2, the 35 plane of the section being at right angles to that of Fig. 2. Fig. 6 is a detail view showing the slot and pin connection between the gear segment and the arm upon the operating rod.

40 Referring to the drawings by numerals, 1 denotes a suitable base plate or support from which projects an upright 2. The latter has its lower end screwed into the base, as seen in Fig. 2, and adjacent to its center is formed 45 an annular enlargement 3, the outer surface of which is of polygonal shape for the reception of a wrench or similar tool by means of which the upright may be rotated. In the upper end of the upright is formed a longitudinally extending opening or bore 4, the lower end of which opens into a transverse slot 5 which also extends longitudinally.

50 Arranged upon the lower portion of the upright is a rotary sleeve 6 having at its ends 55 cone seats for annular rows of bearing balls

7, 8. The upper balls 7 are retained upon their seats by a cone ring 9 which surrounds the upright and abut against the enlargement or integral nut 3. The balls 8 of the lower series are held upon their seat by a 60 similar cone ring 10 which surrounds the upright and is held in an adjusted position by a sleeve 11 which forms an adjusting nut for the bearings. This sleeve 11 is threaded upon the lower end of the rod and has at its 65 lower end a polygonal shaped portion 12 adapted to receive a wrench and adapted, when the upright is screwed into the base to engage the top of the latter. It will be seen that by loosening or screwing the upright 70 partially out of its base, the sleeve or nut 11 may be turned for the purpose of adjusting the bearing balls 7, 8. At the lower end of the rotary sleeve 6 is provided a beveled gear 75 13 which meshes with and is driven by a similar gear 14 upon a horizontal shaft 15. At the upper end of the sleeve 6 is an annular enlargement or collar formed at diametrically opposite points with spaced ears or lugs 16 between which are pivoted by screws or 80 the like 17 the lower ends of links 18.

The links 18 have pivoted in their bifurcated upper ends arms 19 which carry upon their lower ends centrifugal balls or weights 20. The upper ends of the arms 19 are bifurcated and pivoted upon ears 21 formed at diametrically opposite points upon a collar or sleeve 22 which surrounds and rotates upon an inner sleeve 23 mounted for sliding movement upon the upper portion of the upright 2. The inner sleeve 23 has at its lower end an annular flange or collar 24 and projecting through it and through the transverse slot 5 in the upright is a cross piece or pin 25. The latter is adapted to slide in the slot 5 as 95 the sleeve 23 is moved longitudinally upon the upright and screwed into its central portion is the lower end of a rod 26 which extends through the bore or central opening 4 in the top of the upright and is adapted to 100 operate an indicating mechanism presently described.

To reduce friction between the rotating sleeve 22 and the sliding sleeve 23 I provide two annular rows 27, 28 of bearing balls. The balls of each series engage cone seats formed within the outer sleeve 22 and those of the lower series are held upon their seats by a cone ring 29 which surrounds the sleeve 23 and engages the shoulder formed by the 110

flange 24. The balls of the upper series are held upon their seats by a similar cone ring 30 which surrounds the sleeve 23 and is retained in position by a sliding collar 31 adapted to be secured in an adjusted position by a set screw 32. This collar 31 permits the bearing balls 27, 28 to be properly adjusted as will be readily understood upon reference to Fig. 2. When the sleeve 6 is rotated its motion will be imparted through the connecting arms or links to the sleeve 22 and the balls or weights 20 will be thrown outwardly so that the sliding sleeve 23 will be drawn downwardly against the tension of a coil spring 32 which surrounds the upright 2 and is confined between the bottom of the sleeve 23 and a nut 33. The latter is screwed upon a threaded portion 34 of the upright immediately above the enlargement 3 and its outer surface is preferably knurled so that it may be readily turned to vary the tension of said spring.

An indicating device is removably mounted upon the top of the upright 2 and comprises a dial plate 34^a having upon its front suitable graduations 35 and an annular rim or flange which supports a glass covering 36. Projecting rearwardly from the lower portion of the plate 34^a is a lug 37 apertured to receive the upper end of the upright 2 and adapted to be removably and suitably secured thereon by a set screw 38. A cylindrical casing 39 fits over the lug 37 and surrounds the rear portion of the plate 34^a to inclose the operating parts which it carries. This casing is removably secured upon the plate 34^a by threaded studs 40 which project from the rear of said plate and through apertures in the casing and have milled nuts upon their outer ends, as clearly shown in Fig. 3.

Mounted in suitable bearings upon the dial plate 34^a is a concentrically arranged shaft 41 provided upon its outer end with a pointer 42 to co-act with the graduations 35 and upon its inner end with a pinion 43 adapted to mesh with a gear segment 44 which is suitably pivoted or journaled upon the dial plate. This segment is formed with a slot 44^a to receive a pin upon a link or arm 45 which latter is apertured adjacent to one of its ends to receive the upper end of the rod 26 which latter is adjustably secured in said aperture by a set screw 46. A hair spring 47 is provided between the shaft 41 and its bearing or support for the purpose of overcoming lost motion in the segment and pinion and keeping the same at a fixed tension.

The shaft 15 is mounted in suitable ball bearings 48, 49 arranged in upright bearings 60 or supports 50 upon the base 1 and secured upon said shaft intermediate its bearings is an upright wheel 51. The shaft 15 may be connected to the shaft of an engine or a counter shaft in any suitable manner but I preferably provide upon the outer end of the

shaft 15 a beveled pinion 52 adapted to mesh with a similar one upon the driving shaft.

The operation of the machine will be readily understood from the foregoing description taken in connection with the drawings. It will be seen that when the shaft 15 is rotated its motion will be imparted through the beveled gears 13, 14 to the sleeve 6 which latter will cause the sleeve 22 and the connecting links to rotate. As these links or arms rotate the balls 20 fly outwardly and draw the sleeve 23 downwardly upon the upright 2. As the sleeve 23 moves downwardly it carries the rod 26 with it and owing to the connection of the upper end of said rod with the segment or quadrant 44 the latter will be turned to rotate the pinion 43 and hence the shaft 41 and its pointer or indicating hand 42. As the latter travels over the dial it indicates the movement or revolutions of the shaft of the engine or of any other machine upon which the device is used.

By constructing the device as set forth it will be seen that it is especially well adapted for use upon a marine engine since it will not be affected by the rolling or rocking of the ship. The ball bearing mountings for the two rotary sleeves and the substantial connections between said sleeves render the structure strong and durable and the provision of the fly wheel upon the shaft 15 tends to further steady the parts while in operation so that the reading of the same will not be affected by the movement of the ship.

While the machine is especially well adapted for marine use it will be understood that it may be used upon engines or machines of any description where it is desired to indicate the speed or the movement or revolutions of a shaft or other rotary element.

Having thus described my invention what I claim and desire to secure by Letters Patent is:—

1. In an indicator of the character described, an upright having a transverse longitudinally extending slot and a longitudinal opening extending from said slot to its top, a sliding sleeve surrounding said upright, a cross piece carried by said sleeve and extending through said transverse slot in the upright, an indicating mechanism, a rod extending through the longitudinal opening in the upright and connected at its upper end to said mechanism and at its lower end to said cross piece, a rotary sleeve upon said upright, a rotary sleeve upon said sliding sleeve and links connecting said rotary sleeves and carrying centrifugal weights.

2. In an indicator of the character described, an upright having a transverse longitudinally extending slot and a longitudinal opening extending from said slot to its top, a sliding sleeve surrounding said upright, a cross piece carried by said sleeve and extending through said transverse slot in the up-

- right, an indicating mechanism, a rod extending through the longitudinal opening in the upright and connected at its upper end to said mechanism and at its lower end to 5 said cross piece, a rotary sleeve upon said upright beneath said sliding sleeve, a rotary sleeve upon said sliding sleeve, centrifugal devices connecting said rotary sleeves, a coil spring surrounding said upright and engaged 10 with the lower end of said sliding sleeve and an adjusting nut upon said upright and engaged with the lower end of said coil spring.
3. In an indicator of the character described, an upright having a transverse longitudinally extending slot and a longitudinal opening extending from said slot to its top, a sliding sleeve surrounding said upright, a cross piece carried by said sleeve and extending through said transverse slot in the upright, an indicating mechanism, a rod extending through the longitudinal opening in the upright and connected at its upper end to 15 said mechanism and at its lower end to 45 said cross piece, a rotary sleeve upon said upright, a rotary sleeve upon said sliding sleeve, centrifugal weight carrying links connecting said rotary sleeves, anti-friction ball bearings for each of said rotary sleeves, a 50 shaft, anti-friction ball bearings therefor, a fly wheel upon said shaft and gearing connecting said shaft and said rotary sleeve upon the upright.
5. In an indicator of the character described, an upright having a transverse longitudinally extending slot and a longitudinal opening extending from said slot to its top, a sliding sleeve surrounding said upright, a cross piece carried by said sleeve and extending through said transverse slot in the upright, a centrifugal device for actuating said sliding sleeve, a dial plate having an apertured portion to receive the upper end of said upright, a set screw for clamping said dial plate upon said upright, a concentric shaft mounted in said dial plate, a pointer upon said shaft, a pinion upon said shaft, a gear segment to mesh with said pinion, a link connected to said segment and having an aperture to receive the upper end of said rod and a set screw for clamping said rod in said aperture. 55 60 65 70
- 35 4. In an indicator of the character described, an upright having a transverse longitudinally extending slot and a longitudinal opening extending from said slot to its top, a sliding sleeve surrounding said upright, a cross piece carried by said sleeve and extend- 40
